DESIGN FOR A LAMP OR SIMILAR ARTICLE

Paul E. Allen, Skokie, and Edward W. Beatty,
Chicago, Ill., assignors, by direct and mesne assignments,
to Baby's Pal Company, Chicago,
Ill., a corporation of Illinois

Application July 27, 1946, Serial No. 132,032

Term of patent 14 years

(Cl. D48—20)

To all whom it may concern:

Be it known that we, Paul E. Allen and Edward W. Beatty, citizens of the United States, residing at Skokie and Chicago, respectively, in the county of Cook and State of Illinois, have invented a new, original, and ornamental Design for Lamp or Similar Article, of which the following is a specification, reference being had to the accompanying drawing, forming a part thereof.

In the drawing:

Fig. 1 is a perspective view of a lamp or similar article embodying our new design; and

Fig. 2 is a top plan view of a lamp base thereof.

The characteristic features of my design reside in the portions shown in full lines.

We claim:

The ornamental design for a lamp or similar article, substantially as shown and described.

PAUL E. ALLEN.

EDWARD W. BEATTY.
